UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

SEWING-MACHINE.

1,211,493.

Specification of Letters Patent.

Patented Jan. 9, 1917.

Application filed January 5, 1912. Serial No. 669,574.

To all whom it may concern:

Be it known that I, DUDLEY S. SEYMOUR, a citizen of the United States, residing at Oak Park, in the county of Cook, State of Illinois, have invented certain new and useful Improvements in Sewing-Machines, of which the following is a description, reference being had to the accompanying drawing, and to the letters and figures of reference marked thereon.

The invention relates to new and useful improvements in sewing machines, and more especially to the looper-operating mechanism and the feeding mechanism therefor.

An object of the invention is to provide a combined looper and feed-operating mechanism, wherein the feed dog and the looper are given all their movements from two eccentrics mounted on an upper rotary shaft.

A further object of the invention is to provide an arrangement of parts whereby the feed dog is given a proper dwell during the feeding and the return strokes thereof, and wherein the looper is given proper dwell at the forward end of its stroke, while the same is being moved laterally to avoid the needle.

These and other objects will in part be obvious, and will in part be hereinafter more fully described.

In the drawings which show by way of illustration one embodiment of the invention,—

Figure 1 is a vertical sectional view longitudinally through a sewing machine embodying the improvements; Fig. 2 is a front view of the same; Fig. 3 is a horizontal sectional view, showing the feeding mechanism and looper mechanism in plan; Fig. 4 is a vertical sectional view transversely through the standard; Fig. 5 is a detail perspective view, showing the feed-operating mechanism and the looper-operating mechanism; Fig. 6 is an end view of the cylindrical bed plate with the front cap removed; Fig. 7 is a diagrammatic view of the looper-oscillating mechanism and the devices for giving one of the feed movements; and Fig. 8 is a similar view, showing the parts in a different position.

The invention is herein shown as applied

to a sewing machine, which consists of a vertical standard 1, on which is supported a cylindrical bed plate 2. Said standard 55 carries an overhanging arm 3, in which is mounted the main rotating shaft 4. The needle bar 5 reciprocates in the forward end of the overhanging arm, and, as herein illustrated, is provided with two pairs of needles 60 6, 6. The needle bar is connected to a crank on the end of the main shaft by a link 7. The bed plate is formed with a slotted offset 100, to guide the looper threads.

The needle threads are carried through 65 suitable thread-controlling devices mounted on the overhanging arm, which controlling devices are operated by an eccentric 8 carried by the main shaft. These thread-controlling devices are shown, described and 70 claimed in my co-pending application Serial No. 658,553, filed November 4th, 1911, and as the same form no part of the present invention, they will not need further description.

Cooperating with each pair of needles 6, 6, is a looper 9. These loopers are mounted on a looper carrier, which is pivoted at 10 to a looper-supporting shaft 11. The looper-supporting shaft 11 is mounted in suitable 80 bearings and extends longitudinally of the cylindrical bed plate 2. The looper carrier is oscillated through a link 12, and said loopers are moved laterally to avoid the needle by oscillating the looper-supporting 85 shaft 11.

The fabric is presented to the needles by a feed dog 13. This feed dog 13 is rigidly carried by a frame 14, which is supported so that the same may be rocked laterally 90 by a feed rocker 15. A shaft 16 extends longitudinally of the cylindrical bed plate, and is mounted in bearings, so that the same may be oscillated. This shaft carries two spaced arms 17 and 18, which form the feed 95 rocker 15, and the frame 14 is pivotally supported by the arms 17 and 18.

The oscillations of the shaft 16 will bodily raise and lower the frame 14, and thus carry the feed dog into and out of engagement with the material. The frame 14 is oscillated through a crank 19, adjustably carried by the end of a shaft 20. This shaft 20 is also mounted in suitable bearings in

the bed plate. The crank 19 is connected by a link 21 with a pin 22, rigidly carried by the frame 14. This shaft 20 is oscillated, and as it is oscillated, the frame is swung about its pivotal support and the feed dog moved back and forth for the feeding movements.

The looper-supporting shaft is oscillated by an eccentric 23, which is carried by the oscillating shaft 20, and an eccentric strap 24 coöperating with the eccentric 23 is pivotally connected to an adjustable stud 25, carried by an arm 26, rigidly attached to the looper-supporting shaft 11.

15 Mounted on the main shaft 4 is an eccentric 27. A link 28 coöperates with the eccentric 27. A cross shaft 29 is mounted in suitable bearings in the standard, and said cross shaft carries a collar 30 provided with

20 spaced arms 31, 31, and these parts form a rocking member. The link 28 at its lower end is connected with a ball stud, which is mounted on one of the arms 31, so that as the main shaft rotates, the cross shaft 29

25 will be oscillated through the link 28. A second cross shaft 32 is mounted in suitable bearings in the standard, and said cross shaft is provided with a collar 33 carrying spaced arms 34. A link 35 is pivoted be-

30 tween the spaced arms 34, and the spaced arms 31. The shaft 29, therefore, through the arms 31, link 35 and arms 34, will cause the shaft 32 to oscillate. The shaft 32 is provided with a second collar 36, which car-

35 ries a downwardly projecting arm 37, having a ball stud to which the link 12 is pivoted. The oscillations of the shaft 32 are, therefore, through the link 12 transmitted to the looper carrier, and cause the loopers

40 to move into and out of the needle loops. On the collar 30 is another arm 38. This arm 38 carries a ball stud, to which is pivoted a link 39. The link 39 at its lower end is connected with an arm 40, which is at-

45 tached to the outer end of the shaft 16. The oscillations of the shaft 29, will, therefore, be imparted directly to the shaft 16, and through the rocker 15 will raise and lower the feed dog into and out of engagement with the material.

50 It will, therefore, be seen that the link 28 oscillates the looper into and out of the needle loop, and causes the feed dog to be raised and lowered into and out of engagement with the fabric.

55 On the main shaft 4 is a second eccentric 41, with coöperates with a link 42. The link 42 at its lower end is connected to a ball stud on an arm 43, carried by the end of the shaft 20. The shaft 20, as above noted, 60 through the eccentric 23 oscillates the looper-supporting shaft 11 and moves the loopers laterally to avoid the needle. The shaft 20 also, through the crank pin on the end thereof, oscillates the feed dog-sup-

65 porting frame, and gives to the feed dog its

feeding movements. Therefore, the link 42 not only moves the looper laterally, but also gives the feeding movements to the feed dog.

The looper threads are carried through a 70 thread guide on the outer end of a looper-thread-controlling arm 44. This arm 44 is pivoted to an adjustable bracket 45. Said thread-controlling arm is provided with a projecting part 46, which is connected by 75 a link 47 to an arm 48 on the outer end of the shaft 32. The oscillations of the shaft 32 will, therefore, impart an oscillation to the arm 44. This looper-thread-controlling mechanism is shown, described and claimed 80 in my co-pending application Serial No. 658,556, filed November 4th, 1911, and further description thereof will not be necessary.

The arms 31 carried by the shaft 29, 85 which imparts the forward and backward movement to the looper, move from a position substantially in a horizontal plane, when the looper is at one end of its stroke, to a position inclined to a horizontal plane. 90 When the parts are positioned as shown in Fig. 7, the looper is at the forward end of its stroke. At this time, the arms 31 and the link 35 are substantially in alinement, and, therefore, the looper is given an extended dwell while at the forward end of its stroke. This particular looper mechanism *per se*, is shown, described and claimed 95 in my co-pending application Serial No. 658,555, filed November 4th, 1911.

The arm 38 moves from a position slightly at one side of a vertical plane passing through the axis of the shaft 29, to a position considerably at the other side 100 thereof.

When the parts are positioned as shown in Fig. 8, the arm 38 and the link 39 are substantially in line, and, therefore, little or no movement will be imparted to the arm 40 and the shaft 16 oscillated thereby. 110 When these parts are positioned as shown in Fig. 7, any movement of the arm 30 will impart a movement to the arm 40. When the parts are positioned as shown in Fig. 8, the feed dog is beneath the work support, 115 and when the parts are positioned as shown in Fig. 7, the feed dog is above the work support. It will, therefore, be seen that the feed dog will be raised quickly into engagement with the fabric, held in engagement 120 with the fabric a short time owing to the dwell in the movement of the link 28 through the action of the eccentric operating the same, moved quickly out of engagement with the fabric and held out of engagement with the fabric a considerable time through the dwell caused by the arm 38 and link 39 moving into alinement. I have, therefore, provided a feed-operating mechanism, wherein the feed dog is moved 125 130

into and out of engagement from the mechanism which moves the looper into and out of the needle loop, and said mechanism for operating the feed dog is timed to give the desired movements above stated. The necessary dwell in the up and down movements of the feed dog, and also the necessary dwell of the looper while in the needle loop and being moved laterally, are all derived from a single eccentric, by reason of the arrangement of the levers and links which give the desired differential movements.

The arms 31 and the link 35 constitute a toggle mechanism wherein the members of the toggle move into alinement, and thereby produce a dwell in the parts operated through the toggle. The members 38 and 39 also constitute a toggle mechanism which moves into alinement and gives a dwell to the parts operated thereby.

The shaft 20 is oscillated through the movements of the link 42, and, therefore, said shaft will be given a slight dwell at each end of its stroke, while the eccentric is passing the dead center. The oscillation of the shaft 20 through the eccentric 23 carried thereby, vibrates the looper laterally, so that it is given a needle-avoiding movement. This eccentric also slightly increases the dwell given to the looper while it is moving into the needle loop, so that there is substantially no lateral movement of the looper at this time.

By the above mechanism, I have provided devices whereby the looper is moved into and out of the needle loop and the feed dog is raised and lowered by a single eccentric mounted on the upper rotary shaft. The looper is moved laterally to avoid the needle and the feed dog is moved back and forth to feed the material through a second eccentric, mounted on a rotary shaft in the overhanging arm. These devices are so disposed as to give the proper timed movement to the looper and feed dog, and said devices consist entirely of positively operated parts, so that the machine may be given great speed, and is especially adapted for stitching heavy materials such as leather or the like.

The arm 37 which moves the looper into and out of the needle loop, may be adjusted on the shaft 32 by loosening the screw which clamps the arm to the shaft, and by this adjustment of the arm, the vibrating position of the looper is changed. The link 39 may also be adjusted in the usual manner, as this link is provided with a right and left hand thread at each end thereof, and by lengthening or shortening the link, the differential throw given to the arm 40 which controls the looper thread, may be varied. The link 28 may be similarly adjusted as to length, and by this adjustment of the link, the differential throw given to the rocking members 31 and 38 may be varied. By

these various adjustments the looper may be properly timed both as to its forward and backward as well as its lateral throw, and also the thread arm for the looper thread may be properly timed.

By the above construction, a variable movement is given to the looper, and this movement is so timed that the looper will move relatively fast into the needle loop, and relatively slow when the needle is going through the triangle formed by the looper thread, the body of the looper, and the previous needle loop on the looper. Furthermore, by these fast and slow movements, a much shorter looper may be used, without any liability of skipping stitches.

It is obvious that minor changes in the details of construction may be made, without departing from the spirit of the invention as set forth in the appended claims.

Having thus described my invention, what I claim as new and desire to secure by Letters Patent, is:—

1. A sewing machine including in combination, a main rotating shaft, a feed dog, a looper, a needle, means for reciprocating the needle, an eccentric mounted on said main shaft, devices operated from said eccentric for moving the looper into and out of the needle loop and for raising and lowering the feed dog, a second eccentric on the main shaft, and devices operated from said second eccentric for moving the looper laterally, and for giving to the said feed dog a forward and backward movement.

2. A sewing machine including in combination, a standard, an overhanging arm carried thereby, a main rotating shaft in said overhanging arm, a needle, means for reciprocating said needle, a looper, a feed dog, an eccentric on said shaft, a link connected to said eccentric, a shaft in said standard oscillated by said link, devices operated from said shaft for moving the looper into and out of the needle loop and for raising and lowering said feed dog, a second eccentric on said main shaft, and devices operated thereby for moving the looper laterally and for giving the feed dog backward and forward movements.

3. A sewing machine including in combination, a standard, an overhanging arm carried thereby, a rotary shaft mounted in said overhanging arm, a needle, means for reciprocating said needle, a looper, a transverse shaft mounted in the standard, an eccentric on said rotary shaft, a link co-operating therewith for oscillating said transverse shaft, a second transverse shaft in said standard, devices for oscillating said second transverse shaft from said first named transverse shaft, devices for moving the looper into and out of the needle loop operated by said second transverse shaft, devices operated from said first named shaft for raising

and lowering the feed dog, and means for giving the feed dog a backward and forward movement.

4. A sewing machine including in combination, a standard, an overhanging arm carried thereby, a rotary shaft mounted in said overhanging arm, a needle, means for reciprocating said needle, a looper, a transverse shaft mounted in the standard, an eccentric 10 on said main shaft, a link coöperating therewith for oscillating said transverse shaft, a second transverse shaft in said standard, devices for oscillating said second transverse shaft from said first named transverse shaft, 15 devices for moving the looper into and out of the needle loop operated by said second transverse shaft, devices operated from said first named shaft for raising and lowering the feed dog, a second eccentric on said main 20 shaft, and devices operated from said second eccentric for moving the looper laterally and for giving the feed dog a forward and backward movement.

5. A sewing machine including in combination, a looper, a feed dog, a main rotating shaft, an eccentric carried by said main shaft, a transverse shaft oscillated from the eccentric on the main shaft, a toggle mechanism operated by said transverse shaft for 25 giving one movement to the looper, and a toggle mechanism operated by said transverse shaft for giving one movement to the feed dog.

6. A sewing machine including in combination, a work support, a looper, a feed dog, a main rotating shaft, an eccentric carried by the main rotating shaft, a transverse shaft oscillated from said eccentric, a toggle mechanism actuated by said transverse shaft 35 for moving the looper into and out of the needle loop and giving a dwell at the forward end of its stroke, and a second toggle mechanism operated from said transverse shaft for raising and lowering the feed dog 40 and giving a dwell thereto while beneath the work support.

7. A sewing machine including in combination, a main rotating shaft, a looper, a feed dog, a transverse shaft, a collar mounted on said transverse shaft, arms carried by said collar and projecting at angles to each other, means for connecting one of the arms to the main shaft, whereby said transverse shaft is oscillated, means also connected to 50 said arm for moving the looper into and out of the needle loop, devices carried by the other arm carried by the collar for raising and lowering the feed dog.

8. A sewing machine including in combination, a looper, a shaft, means for oscillating the shaft, a second shaft, devices for connecting said second shaft to the looper, means for operating the second shaft from 60 the first named shaft and giving a dwell thereto, a take-up for the looper thread, and

devices operated from the second shaft for oscillating said take-up and giving an increased dwell thereto.

9. A sewing machine including in combination, a looper, a shaft, means for oscillating the shaft, a second shaft, devices for connecting said second shaft to the looper, means for operating the second shaft from the first named shaft and giving a dwell thereto, a take-up for the looper thread, devices operated from the second shaft for oscillating said take-up and giving an increased dwell thereto, a feed dog, and devices operated from said first named shaft for raising and lowering the feed dog. 70 75 80

10. A sewing machine including in combination, a looper, a shaft, means for oscillating the shaft, a second shaft, devices for connecting said second shaft to the looper, means for operating the second shaft from the first 85 named shaft and giving a dwell thereto, a take-up for the looper thread, devices operated from the second shaft for oscillating said take-up and giving an increased dwell thereto, a feed dog, devices operated from 90 said first named shaft for raising and lowering the feed dog, said feed dog-operating devices including a toggle mechanism for giving a dwell to the movements of the feed dog. 95

11. A sewing machine including in combination, a standard, an overhanging arm, a looper, a feed dog, a main shaft mounted in said overhanging arm, an eccentric carried by said main shaft, a transverse shaft 100 mounted in the standard, a link coöperating with said eccentric for oscillating said transverse shaft, a second transverse shaft parallel to the first named transverse shaft, toggle links for imparting an oscillation from 105 the first named transverse shaft to said second transverse shaft, devices for oscillating the looper from said second transverse shaft, a take-up for the looper thread, and devices operated by said second transverse shaft for 110 vibrating said take-up.

12. A sewing machine including in combination, a standard, an overhanging arm, a looper, a feed dog, a main shaft mounted in said overhanging arm, an eccentric carried by said main shaft, a transverse shaft 115 mounted in the standard, a link coöperating with said eccentric for oscillating said transverse shaft, a second transverse shaft parallel to the first named transverse shaft, toggle links for imparting an oscillation from 120 the first named transverse shaft to said second transverse shaft, devices for oscillating the looper from said second transverse shaft, a take-up for the looper thread, and devices 125 operated by said second transverse shaft for vibrating said take-up, said take-up vibrating devices including a toggle lever, whereby said take-up may be given a dwell. 125

13. A sewing machine including in com- 130

bination, a standard, an overhanging arm, a looper, a feed dog, a main shaft mounted in said overhanging arm, an eccentric carried by said main shaft, a transverse shaft 5 mounted in the standard, a link coöperating with said eccentric for oscillating said transverse shaft, a second transverse shaft parallel to the first named transverse shaft, toggle links for imparting an oscillation from the 10 first named transverse shaft to said second transverse shaft, devices for oscillating the looper from said second transverse shaft, a take-up for the looper thread, devices operated by said second transverse shaft for vibrating said take-up, and devices operated 15 from said first named transverse shaft for raising and lowering the feed dog.

14. A sewing machine including in combination, a standard, an overhanging arm, a looper, a feed dog, a main shaft mounted in said overhanging arm, an eccentric carried by said main shaft, a transverse shaft mounted in the standard, a link coöperating with said eccentric for oscillating said transverse 25 shaft, a second transverse shaft parallel to the first named transverse shaft, toggle links for imparting an oscillation from the first named transverse shaft to said second transverse shaft, devices for oscillating the looper 30 from said second transverse shaft, a take-up for the looper thread, devices operated by said second transverse shaft for vibrating said take-up, said take-up vibrating devices including a toggle lever, whereby said take-up 35 may be given a dwell, and devices operated from said first named transverse shaft for raising and lowering the feed dog.

15. A sewing machine including in combination, a standard, an overhanging arm, a looper, a feed dog, a main shaft mounted in said overhanging arm, an eccentric carried by said main shaft, a transverse shaft mounted in the standard, a link coöperating with said eccentric for oscillating said 45 transverse shaft, a second transverse shaft parallel to the first named transverse shaft, toggle links for imparting an oscillation from the first named transverse shaft to said second transverse shaft, devices for oscillating 50 the looper from said second transverse shaft, a take-up for the looper thread, devices operated by said second transverse

shaft for vibrating said take-up, said take-up vibrating devices including a toggle lever, whereby said take-up may be given a 55 dwell, and devices operated from said first named transverse shaft for raising and lowering the feed dog, said feed dog operating devices including a toggle lever for giving a dwell to the movement of the feed dog. 60

16. In a sewing machine, a main shaft, a feeding mechanism, a looper mechanism, and means for operating said mechanisms from said main shaft, including a rocking member having two arms, a link connected with 65 one of said arms, and forming therewith a toggle, a third arm connected to said link and having its connection moving substantially in a horizontal line, a link connected to said second arm and forming therewith 70 a toggle, a fourth arm connected to said last named link, and having its connection moving in substantially a vertical line.

17. In a sewing machine, a main shaft, a needle, a looper, a feed dog, means carried 75 on the end of the main shaft for reciprocating the needle, an eccentric carried by said main shaft, devices operated from said eccentric for giving the looper one of its movements and the feed dog one of its movements, a second eccentric carried by said main shaft, and devices operated therefrom, for giving the looper its other movement and the feed dog its second movement. 80

18. In a sewing machine, a main shaft, a needle, a looper, a feed dog, means carried 85 on the end of the main shaft for reciprocating the needle, an eccentric carried by said main shaft, devices operated from said eccentric for giving the looper one of its movements and the feed dog one of its movements, a second eccentric carried by said main shaft, and devices operated therefrom for giving the looper its other movement, and the feed dog its second movement, a 90 looper thread controller and devices operated from one of said eccentrics for oscillating said looper thread controller. 95

In testimony whereof I affix my signature, in presence of two witnesses.

DUDLEY S. SEYMOUR.
